pany Limited, London, England

Application November 9, 1935, Serial No. 49,003
In Great Britain November 14, 1934

4 Claims. (Cl. 179—18)

The present invention relates to telephone systems and more particularly to systems in which common apparatus is called into use temporarily to aid in the setting up of a connection.

5 In a system in which temporary use is made of common apparatus it is important that such apparatus should be released as soon as possible after it has fulfilled its purpose. If such apparatus includes a searching device the release of 10 the apparatus is liable to delay if the search has been unsuccessful and the release is under the control of a subscriber or operator who has to be given a busy signal consequent on the unsuccessful search, or if the release is brought about 15 by a slow acting time limit device.

In the present invention arrangements are provided in a system employing backwardly hunting switches, hereinafter referred to as finder switches, in the conversational path which are taken into use by temporarily used common apparatus wherein, if on the demand arising no free finder switch is available the common apparatus is immediately released. It is a feature of the invention that the release is effected 20 by removing the starting condition which caused the common apparatus to be taken into use. According to a further feature of the invention when no free finder switch is available a signal is transmitted from the common apparatus to a preceding circuit which brings about the removal of the starting signal and may bring about 25 the transmission from the preceding circuit of a busy signal. The common apparatus may serve a plurality of groups of finders the group to be 30 searched being determined by marking applied by a relay responsive to the starting signal. The common apparatus may take the form of an allotter comprising a hunting switch and control circuits therefor and arrangements may be provided whereby it is ensured that the whole of a 35 desired group of finder switches is searched before the signal to the preceding circuit to bring about the release of the allotter is transmitted.

This is of importance in the case of homing type 40 switches where two or more switches are started in response to a starting signal since a group may be marked in response to a starting signal after the hunting switch has entered it. In order to ensure that the whole of a marked group is 45 searched before the allotter can be released it is arranged that the signal to be given when the hunting switch has tested the last finder of a group and has found it engaged is dependent on the prior receipt of a signal indicative of the fact 50 that the first finder of that group has been tested.

In order to overcome the restriction placed on the number of outlets per group of the allotter by providing a separate stopping or "last contact" position for each group to cater for the "all outlets busy" condition it is arranged that the busy 5 signalling condition is brought about when the common apparatus tests the last finder in a marked group if this finder and the remainder of the finders of the group are busy. Such an arrangement may be carried out by preparing 10 the circuit of a relay when the first finder of the group is tested and operating the relay when the last finder of the marked group is reached and if the search has been unsuccessful the operation 15 of the relay in conjunction with the non-operation of the test relay brings about the release of the allotter and the transmission of the signal to a preceding circuit to bring about the transmission therefrom of a busy signal. The signalling circuit to the preceding circuit may 20 include a wiper of the allotter and the circuit over which the common apparatus is taken into use.

For the simplification of the starting arrangements where a plurality of homing allotters is available to a calling circuit and to minimize delay when a number of calls are present simultaneously it may be arranged to start up more than one allotter to search for a free call finder and for the prevention of double seizure by allotters the starting arrangements are such that 25 30 allotters are started in succession after a delay period, the delay period providing for the disabling of a further allotter after a call finder has been seized. Cross connections between allotters may be provided such that the first to find 35 a free call finder creates an artificial busy condition so far as the remaining allotters are concerned, it being arranged that the delay in starting an allotter is not less than the time taken 40 after the finding of a free call finder to apply the artificial busy condition.

An embodiment of the invention is shown by way of example in the accompanying drawings which will now be referred to.

Fig. 1 shows a cord circuit to which access is 45 had over call finders, Fig. 2 shows in the upper part a jack circuit and a jack finder associated with a P. B. X. line, while Fig. 3 shows in the upper part the line circuit of a P. B. X. line. In the lower part of Figs. 2 and 3 is shown a homing 50 type allotter for allotting a jack finder associated with a free P. B. X. line when required.

The operation of the cord circuit shown in Fig. 1 will now be described. The circuit tests free to an allotter for allotting a call finder to 55

- deal with the call by reason of the battery connection to wire P over contact *m*5. When the connection to the cord circuit is switched through by the call finder, relay L operates over the calling loop, the earth connection being over contacts *j*5, *j*6 and *n*6. Contact *l*1 closes a circuit for relay B. Relay B operates and at contact *b*1 connects earth to wire P to mark the circuit engaged and at contact *b*5 connects earth over contact *j*6 to lamp AL which serves as a calling lamp and calling supervisory lamp. Lamp AL lights up. Contact *b*4 connects earth over windings (I) of relays N and M in the plug sleeve circuit. The operator's instrument is connected to the calling line over contacts *m*2 and *m*3 and the operator ascertains the caller's requirements. She then inserts the plug CP into an appropriate jack. If the called line is free, operation of the cut off relay applies battery potential over a low resistance to the bush of the jack and relay N is operated. This relay locks up by means of its winding (II) over contacts *n*1, *j*5 and *b*2 and at contact *n*5 connects earth directly to the plug sleeve to engage the line and short circuits its winding (I) and winding (I) of relay M and completes a circuit for the latter relay to operate on its winding (II). Relay M is differentially wound. When a plug is removed from the shelf, contacts PSC close and relay M having operated, a locking circuit is closed over winding (III) of the relay, contacts *m*1 and PSC. Contact *m*7 opens the operating circuit for relay M. Contacts *m*2 and *m*3 disconnect the operator's instrument circuit from the cord circuit, contact *m*4 closes a circuit for the called supervisory lamp CL over contact *d*2, contact *m*5 disconnects the battery potential signifying a free cord circuit from wire P and contact *m*6 closes an operating circuit for relay J over contact *b*2. Relay N having operated, the tip and ring conductors of the plug are connected up over contacts *n*2 and *n*3 and a leak circuit to enable the caller to hear ringing signal is closed at contact *n*4. The circuit over the busy tone lead BS is disconnected at contact *n*6 before relay J operates, and earth is connected directly to relay L. On the operation of relay J contact *j*1 substantiates contact *b*1, contacts *j*2 and *j*3 apply ringing current over leads RC to the called line, contact *j*4 closes a point in the metering circuit over wire MP, and contact *j*6 extinguishes the lamp AL leaving this now dependent on relay L for further illumination. When the called subscriber replies to the ring, relay F operates by means of its winding (I) over the called loop in known manner and locks up over its winding (II), contacts *f*1 and PSC. Contacts *f*2 and *f*3 disconnect the ringing leads from the plug and connect the called line to the feeding bridge and relay D operates over the called subscriber's loop. Contact *f*4 closes a further point in the metering circuit, contact *f*5 changes over to hold relay N dependent on the continued operation of relay D and contact *f*6 opens a further point in the busy tone lead BS. Relay D having operated, contact *d*1 holds relay N over its winding (II) and contact *f*5 and contact *d*2 extinguishes lamp CL. The calling and called parties are now in communication with one another.
- At the end of the conversation the supervisory lamps are lit as each subscriber clears. If the caller is the first to clear, relay L releases and at contact *l*2 completes a circuit over contact *m*4 for lamp AL. Contact *l*1 releases relay B which releases relay J at contact *b*2 and at con-

tact *b*3 closes the metering circuit. The call is metered during the slow release of relay J by the application to wire MW of suitable potential connected to wire MP. Contact *b*5 opens to guard against continued glowing of lamp AL after the release of relay J and contact *b*4 opens in the operating circuit for relay N. The busy marking is removed from the cord circuit at contacts *b*1 and *j*1 but the battery potential to wire P since relay M is still operated. When the called party clears, relay D releases and at contact *d*1 opens the holding circuit for relay N and at contact *d*2 completes the circuit for lamp CL. Release of relay N disconnects the plug from the cord circuit. The operator seeing both lamps glowing withdraws the plug from the jack and on the restoration of the plug to the shelf, contact PSC opens and relays F and M are released. Contacts *m*2 and *m*3 re-connect the leads to the operator's instrument circuit and contact *m*4 extinguishes the supervisory lamps.

If the wanted line were one connectable to the jack over a finder switch, there would be no indication of its condition at the time of plugging into the jack; consequently if the line was busy there would be no indication of this until its condition had been ascertained by apparatus associated with the finder switch. Arrangements of this nature are shown in Figs. 2 and 3 and will be fully described hereafter. Immediately the plug is inserted into the jack relay N will not be operated owing to the resistance connected between battery and the bush of the jack. If a busy condition is encountered earth will be connected in subsequent apparatus to the bush of the jack and relay M will be operated but not relay N. No connection over the cord is therefore completed and the busy signal lead BS is not interrupted. Relay M locks up and brings about the operation of relay J but relay F is not operated. Consequently busy tone is transmitted to the caller over lead BS, contacts *j*5, *j*6, and *n*6. The connection is taken down when the caller clears as both supervisory lamps will now be glowing.

The system is one in which metering takes place, even though the called subscriber fails to answer, on the release of relay B when the calling subscriber clears, the circuit being over contact *n*7 and back contact *f*4.

If the jack of the wanted line is already plugged the operator will insert the plug into a special busying jack the bush of which will be earthed. Relay M will be operated and busy tone transmitted to the caller in the manner above described.

The complete operation of the circuits shown is described in the application of William G. Patterson and Reginald G. Dixon, Serial No. 48,952, filed Nov. 9, 1935, only those parts of the cord circuit and their operation being shown herein as are necessary for the understanding of the present invention.

The jack CJ shown on the left of Fig. 2 to which reference will now be had may be considered as one in which an operator may insert the plug CP of Fig. 1. The finder JF is one of a number multiplied to a group of jacks which serve the lines of a P. B. X. group. There may be 100 lines in the multiple distributed over a number of P. B. X. groups. Each jack finder is connected to one line of a group which is shown in Fig. 3 at SUB together with the line circuit of that line denoted 75

by the single step line and cut off relays LC and KC respectively.

The jack finders of a number of P. B. X. groups are multipled in the banks of two allotters, one allotter FA being shown in the lower part of Figs. 2 and 3. The allotters are 50 outlet switches and the jack finders 100 outlet switches, both being of the high speed motor driven type.

Associated with jack CJ is a sleeve relay S and a cut off relay CO. The jack finder motor is designated JFM and is represented as a magnet and the allotter motor FAM is similarly shown but the actual driving device is an electric motor the circuit of which is controlled by a latch magnet which also withdraws from and inserts into the driving mechanism a latch, the engagement of the latch with the mechanism bringing the switch to rest immediately on operation of the test relay. The test relay for the finder JF is situated in the allotter circuit and is designated K, that for the allotter being designated C. H is the switching relay. The start relay is designated CS and a pair of relays SA and SB are associated with two allotters for closing the starting circuits of the allotter in which relay A is situated. Relay SB is heavily slugged to retard its operation by 100 to 200 milliseconds after the operation of relay SA.

The terminals designated AT are commoned and connected in groups to contact s2 of sleeve relay S of the jacks concerned with a P. B. X. group. These terminals are cross connected in groups to terminals CT corresponding to positions on the allotter bank connected to jack finders of a group, the terminals of a group in CT being commoned. The terminals DT are also connected in groups to contacts in the allotter bank corresponding to jack finders of a group. Of these contacts those corresponding to the first and last lines of a group are cross connected to the corresponding commoned contacts in set AT. Terminals BT are commoned similarly to terminals AT and are connected to contacts s4 of the jack circuits. They are connected to the contact in the group of terminals ET corresponding to the last contact associated with a group of jack finders in the allotter bank. The terminals FT are commoned in group and connected to contacts in both allotter banks corresponding to jack finders. Terminals GT are similarly commoned. Relays SS and ZZ are concerned with the forced release of an allotter if it is held beyond a predetermined time. The allotter shown may be considered as the first allotter to be started on receipt of a start signal, the starting circuit being shown in chain dotted lines while the starting circuit for the later allotter to be started is shown in dotted line. The rectifier R2 prevents operation of relays C, E and G through the commoning of terminals AT by earth connected over wiper FA7.

The operation of the circuits is as follows: When a plug is inserted into jack CJ, relay S which is of high resistance is operated but relays M and N in the cord circuit do not operate. Contact s1 connects earth to start relay CS, contact s2 connects earth to the commoned terminals AT, contact s3 connects the right hand winding of relay CO to the jack finder test bank contact and contact s4 connects the bush of the jack to the commoned terminals BT. Relay CS operates and at contact s1 closes the following circuit: earth over the dotted line connection, off normal contacts on2 of the first allotter FA, the common point SC, off normal contacts corresponding to on2 of the second allotter, the chain line connec-

tion, contact cs1, relay SA to battery. Relay SA operates and at contact sa1 connects earth over the dotted line connection normal contact wiper FA8 of the allotter, contacts z24 and b4 to relay A. Contact sa2 connects earth to the common point SC to hold relay SA after the allotter moves from normal and contact sa3 closes the circuit for relay SB. Relay A operates in the above traced circuit over wiper FA8 and locks up over contacts t2, a1 and cs2. Contact a2 closes the circuit for relay B over contacts t1, j2 and z22. Relay B operates and at contact b1 closes the circuit for the allotter driving device. This circuit runs from earth over contacts b1, c1, g1, j3, d1, motor FAM to battery. Contact b2 opens a point in the homing circuit for the allotter, contact b3 closes a point in a circuit which includes wiper FA4 to be completed if no free jack finder is available, contact b4 opens the operating circuit of relay A and prepares a circuit to be described hereinafter to prevent the testing-in and to bring about the homing of the second allotter, contacts b5 and b6 prepare circuits for relay SS to be described later and contact b7 connects battery over high speed relay E and back contact f1 to wiper FA7. The motor FAM starts and drives the allotter in search of a free P. B. X. line in the required group. The testing circuit includes wiper FA6 the contacts in the arc of which corresponding to the required group are marked over terminals CT and AT by contact s2 and runs from earth over contact s2, terminals AT, CT, wiper FA6, rectifier R1, contact j4, test relay C which is of the high speed type, wiper FA5, contact lc4, contact kc4, resistance to battery. When the allotter reaches the first contact of the required group, high speed relay E is operated in the following circuit, earth over contact s2, terminals AT, DT, contact corresponding to first line in the group in the contact arc of wiper FA7, wiper FA7, back contact f1, rectifier R2, contact b7, relay E to battery. Contact e1 closes and connects high speed relay F to the back of contact f1 but the relay remains short circuited until the switch leaves the contact over which relay E operated. If and when this occurs, relay F operates in series with relay E and changes over its contact f1 to connect high speed relay G to wiper FA7. If a free line is found relay C operates in the above traced circuit and at contact c1 opens the driving circuit and closes a circuit for relay D. Relays KC and LC operate on their windings (I) and earth over relay C and wiper FA5 is extended over contacts kc3 and lc3 to the test wire in the line finder multiple over which outgoing calls are made. The windings (II) of relays LC and KC are disconnected from the line SUB at contacts lc1, lc2, kc1, kc2 and contact kc4 removes the non-inductive shunt from the windings (I). The allotter is brought to rest and a further point in the driving circuit is opened at contact d1 on the operation of relay D. Contact d2 connects earth over contacts b4, z24 to wiper FA8 the contacts in the arc of which are common in groups so that the earth potential is extended over the commoning and wiper FA8 of the other allotter when it is rotating over contacts of the group, contacts z24, b4, and back contact d2 thereof to its wiper FA5 to mark the lines of the group engaged to the other allotter and prevent its testing in. Contact d3 connects the jack finder test relay K to wiper FA1 and contact d4 connects earth over contact k1 and wiper FA2 to the driving device JFM of the jack finder. Contact d5 connects earth to wiper FA9 which extends it over commoned terminals GT multipled over both

- allotters, wiper FA9 of the second allotter, back contacts *j5* and *d5* thereof to the junction of relay E and the resistance to prevent the initiation of the busy testing arrangements. The motor JFM of the first allotter is started and the jack finder connected to the line seized by the allotter moves off in search of the plugged jack. When this is found, relay K operates in the following circuit, earth over high speed test relay K, contact *d3*, wiper FA1, and contact connected to wiper JF4, contacts corresponding to the group concerned in the wiper arc cross-connected to terminal MT, wiper JF3, contacts *s3*, *co1*, resistance to battery. Relay CO operates after relay K has 10 operated and holds temporarily in series with it over contact *co1*. Contact *co2* disconnects relay CO and connects the left hand winding of relay CO to the bush of the jack. This winding being of considerably lower resistance than that of relay S permits relay N in the cord circuit to operate with results already described in connection with Fig. 1. Relay K operating, contact *k1* opens the jack finder driving circuit to bring the finder to rest and operates relay L. Contact *l1* connects 20 earth over contacts *z22*, *j2*, and wiper FA3 to the right hand winding of relay H, contact *l2* opens to release relay A and contact *l3* opens in the allotter homing circuit. Relay H operates and locks up over its low resistance left hand winding and the high resistance right hand winding of relay CO, the low resistance earth connection marking the jack engaged to further finders. Contacts *h2* and *h3* switch the speaking wires through and contact *h4* connects earth to hold 30 relays LC and KC and to the contact in the arc of wiper FA5 to busy the line to a searching allotter and release relay C. The release of relay A opens the circuit of relay B at contact *a2* and on the subsequent release of relay B relays E and F release. Relay K now being short circuited over contact *h1* releases and releases relay L, and relay D is released by the opening of contact *cl*: The homing circuit for the allotter is now closed and runs from earth over off normal contact *on1*, contacts *l3*, *b2*, *j3*, *d1*, motor FAM to battery and the allotter is rapidly homed its circuit being opened at contact *on1* in the home position.
- When the allotter was first taken into use relay SA operated and was followed after a delay period by the operation of relay SB. Contact *sb1* closes a circuit for relay A of the second allotter which is started. Due to the connection of earth over contact *d2* of the first allotter and the commoned contacts in the arc of wiper FA8 the second allotter is prevented from testing in to a line of the P. B. X. group after the seizure of one by the first allotter since its relay C will be short circuited by the earth in the earlier traced circuit and it continues to rotate until its home position 50 is reached or until a free line in another marked group is found. Relay D (or J if no free available jack finder has been found) in the first allotter will be operated and relay E in the second allotter is prevented from operating when the first contacts of the group searched by the first allotter are reached by reason of a short circuit extending from earth over contact *sa2*, terminals AT and DT, wiper FA1, rectifier R2, contact *b7*, relay E, contacts *d5*, *j5*, wiper FA9, commoned terminals GT associated with the group concerned, wiper FA9 of the first allotter, contact *j5* or contacts *j5* and *d5* therein to earth. The second allotter continues in motion past the group and searches, if necessary in a further marked group.
- 75 When the second allotter leaves its normal posi-

tion its contacts *on2* open and relay SA releases and is followed after an interval by the release of relay SB. Since the starting circuit for the first allotter depends on relay SA and this relay can only be operated when both allotters are at normal the first allotter is prevented from making a research until the second allotter has homed.

As soon as the finder started by the first allotter has found the calling line, relay CS is released if no further call is waiting and at contact *cs2* releases relay A of the second allotter. Contact *a2* opening, relay B is released and the second allotter homes. If another call had been waiting, relay CS would not have released and the second allotter would have searched for a free finder in the marked group.

If the last line of the group is reached during the test for a free line by the first allotter to be started, relay G operates and stops further drive by opening the circuit of motor FAM at contact *g1*. If this line is free, relay C also operates with the result before described and at contact *c1* prevents relay J from operation. If, on the other hand this line is busy, relay C does not operate but relay J does and at contact *j1* connects direct earth over contact *b3*, wiper FA4, terminals ET and BT, contacts *s4* and *co2* (relay S has not been released since relay CO has not been operated), to the bush of the jack. Relay M in the cord circuit is operated but not relay N and the caller receives a busy signal from the cord circuit in the manner already described in connection with Fig. 1. The operation of relay J releases relay B at contact *j2* which in turn releases relay J and the allotter homing circuit is closed. The sleeve circuit being now opened at contact *m7* in the cord circuit, relay S is dependent on relay B and on the release of this relay, relays S, CS, SA, SB and A release if no other call is waiting and the allotter rotates to and remains in its home position. If a call in another group is waiting, relays CS and A will not be released and the release of relay J will cause re-operation of relay B and a renewed search by the allotter.

When the allotter FA is taken into use and relay B is operated, the left hand winding of relay SS is connected over contacts *b6* and *z23* to a wire SSW which is earthed periodically. Relay SS operates on the first earthing on wire SSW after the operation of relay B and locks up over its right hand winding, contacts *ss1* and *b5*. Contact *ss2* prepares a circuit for relay ZZ over wire ZZW which is earthed momentarily after the elapse of a prescribed interval from the earthing of wire SSW. If, during this interval the allotter is released, either as a consequence of its having found a free line and controlled the finder JF to connect this line to the jack CJ or as a consequence of its not being successful in its search for a free line and relay B is released, relay ZZ is not operated. If the allotter is not released within this time relay ZZ is operated and locked up over contact *z21*. Contact *z23* disconnects the left hand winding of relay SS from wire SSW, contact *z25* lights an alarm lamp ZL in a circuit which includes a relay for giving an audible alarm, contact *z22* releases relay B and contact *z24* prevents relay A from operating after the allotter is homed. Relay B releasing, the allotter homes in the manner previously described. Relay ZZ is released by an attendant investigating the cause of the prolonged holding of the allotter by short circuiting the springs ZJ by means of a plug. The alarm lamp ZL is extinguished and the audible alarm

relay released and the circuits are restored to normal.

A release alarm relay is included in the circuits of the motors and latch magnets which are designated as a whole JFM and FAM.

I claim:—

1. In a telephone system, a line, a second line, a group of finders having access to said second line, a start circuit for said finders, means responsive to the establishment of a connection between the first and second lines for placing a calling condition on the second line, thereby closing said start circuit, means responsive to the closure of said start circuit for starting a finder if one is available, means effective if all the finders are busy for transmitting a signal through the established connection between the first and second lines, and means individual to the first line and responsive to the signal for removing the calling condition on the second line.
2. In a telephone system, a plurality of groups of lines, a plurality of groups of finders corresponding, respectively, to said groups of lines, an allotter common to all said finders, means responsive to a calling condition on any line for causing said allotter to search for an idle finder in the group which corresponds to the group in which such calling line is located, and means

effective in case said allotter finds all the finders in such group busy for removing the calling condition from the calling line.

3. In a telephone system, a plurality of groups of finders, an allotter having access to all said finders, means responsive to a call on a line accessible to the finders of a certain group for starting said allotter searching for an idle finder in such group, registering means in the allotter operated responsive to testing of the first finder in such group, registering means in the allotter operated responsive to testing the last finder in the group only if said first registering means has been operated, and means for stopping the operation of the allotter responsive to the call contingent on the operation of both registering means and on all finders in the group being found busy.

4. In a telephone system, a line, a plurality of finders having access to said line, a first allotter common to all said finders, a second allotter common to all said finders, means responsive to a call on said line for starting said allotters successively, and means for introducing a predetermined time interval between the starting of the first allotter and the starting of the second allotter.

REGINALD GRIFFITH DIXON.
